Primary Examiner — Rachel A. Voorhies

Assistant Examiner — Benjamin D. Wannemacher

(74) Attorney, Agent, or Firm — CANTOR COLBURN
 LLP(57) **CLAIM**

I claim, the ornamental design for a pruning shears, as shown and described.

DESCRIPTION

FIG. 1 is a perspective view of pruning shears, showing my new design;

FIG. 2 is left side view thereof;

FIG. 3 is another perspective view thereof; and,

FIG. 4 is a right side view thereof.

1 Claim, 4 Drawing Sheets
